Des. 202,665
Patented Oct. 26, 1965

202,665

CARRIER FOR BOTTLES OR THE LIKE

Louis R. Petrone, East Orange, Frank W. Stevens, Rutherford, and Joseph R. Tino, Clifton, N.J., assignors to W. R. Grace & Co., New York, N.Y., a corporation of Connecticut

Filed Aug. 3, 1964, Ser. No. 81,114

Term of patent 14 years

(Cl. D58—26)

FIG. 1.

FIG. 2.

FIG. 3.

Our design is characterized by the combination of an open tray of the type disclosed with a carrying handle having the particular configuration shown.

We claim:

The ornamental design for a carrier for bottles or the like, as shown and described.
